UNITED STATES PATENT OFFICE.

WILLIAM J. WOERNER, OF ROCHESTER, NEW YORK.

EXTENSIBLE ROD.

Application filed November 17, 1925. Serial No. 69,720.

To all whom it may concern:

Be it known that I, WILLIAM J. WOERNER, a citizen of the United States, and resident of Rochester, in the county of Monroe and 5 State of New York, have invented certain new and useful Improvements in Extensible Rods, of which the following is a specification.

The present invention relates to extensible rods and an object thereof is to provide a rod in which the parts are so connected that they telescope with a minimum amount of friction between them. A further object of the invention is to provide 15 a novel means for guiding the rod parts against turning movement relatively to each other.

To these and other ends, the invention consists of certain parts and combinations of 20 parts, all of which will be hereinafter described: the novel features being pointed out in the appended claims.

In the drawings:

Fig. 1 is a perspective view of the rod 25 employed in connection with a candle snuffer and lighter;

Fig. 2 is a fragmentary longitudinal section through the rod;

Fig. 3 is a section on the line 3—3, Fig. 30 2; and

Fig. 4 is a section on the line 4—4, Fig. 2.

Referring more particularly to the embodiment of the invention illustrated in the drawings, 1 indicates a candle snuffer secured to a curved end 2 of a rod section 3 which also carries a slotted guide 4 for a lighting taper controlled through a slide 5 in the ordinary manner. The rod 3 is a tubular construction and is formed with a 35 longitudinally extending groove 6 in a portion of which the slotted tube 4 lies. This groove is formed by pressing the sheet metal of the hollow tube inwardly so that an interior longitudinally extending rib 7 is formed. 40 In the end of the tube is tightly fitted a block 8 through a drive fit or by brazing, and this block 8 has a screw threaded opening 9. The block is grooved in one side to receive the rib 7 so as to prevent the turning of such block in the tube. A combination guide or stop 10 is also fitted in the end 45 of the tube 3 and has a flange 11 at its outer end abutting the end of the tube 3 and projecting beyond the latter to form a shoulder 50 or abutment 12. This flange 11 is also provided with a notch or groove 13. A screw 55

14 passes through the combined guide and stop and into the anchoring block 8 to hold the combined guide and stop into position on the tube 3.

The tube 3 operates within an intermediate tube 15 which is also provided with a longitudinally extending groove indicated at 16 formed by pressing the sheet metal inwardly to provide an internal rib 17. A sleeve 18 is fitted within the outer end of the tube 15 and is provided with a groove 19 formed by pressing the metal of the sleeve inwardly so that a rib 20 is provided. The groove 19 of the sleeve 18 receives the rib 17 of the tube 15 while the rib 20 of the sleeve 18 projects into the groove 6 of the tube 3, so as to guide the tube 3 at the outer end of the tube 15, the sleeve 18 being brazed or rigidly secured to the tube 15 and being held 70 against turning through its rib and groove connection with the tube 15. A collar 21 fits rigidly about the outer end of the tube 15 and carries a set screw 22 which passes through the tube 15 and the sleeve 18, so as to engage with the bottom of the groove 6 in the sleeve 3. This set screw holds the tube 3 in its adjusted relation on the tube 15 and as it enters the groove tends to not only prevent relative turning between the 75 tube 3 and the tube 15, but also prevents the marring of the outer face of the tube 3. The groove 13 of the combined stop and guide 11 receives the rib 17 of the tube 15 and prevents the turning of the inner end 90 of the tube 3, while the flange 11 by cooperating with the interior walls of the tube 15 acts as a guide for the inner end of the tube 3. This flange also through its abutment 12 cooperates with the inner end of the sleeve 18 to limit the outward movement of the tube 3. By removing the screw 14, the combined guide and abutment member 10 may be disconnected to permit the latter to be withdrawn from the tube 15. On the 100 inner end of the tube 15, a sleeve 23 is rigidly secured by brazing or otherwise and has an end 24 acting as a stop or abutment. This sleeve 23 also acts as a guide for the inner end of the tube 15 when the latter 105 telescopes within a tube 25 to which the handle 26 is secured.

The tube 25 has at its outer end an internal sleeve 27 which is pressed inwardly in the direction of its axis to provide a rib 110 28 operating in the longitudinally extending groove 16 of the tube 15 to guide the

latter at the outer end of the tube 25. This sleeve acts as a stop for engagement with the shoulder 24 on the sleeve 23 to limit the outward movement of the tube 15. Secured externally about the free end of the tube 25 is a collar 28* which carries a set screw 29 that passes through the sleeve 27 for engagement with the bottom of the groove 16 so as to act to prevent the turning of the groove 15 and to engage the tube 15 at a place where it will not mar the main surface of the latter.

From the foregoing it will be seen that there has been provided an extensible rod 15 in which one rod member slides with another and has two point bearing within the latter one at the outer end through a sleeve and at the other end through a combined stop and guide member, whereby the friction 20 between the two rod members is reduced to a minimum, and at the same time the two rod members are held against separation. The combined guide and stop member is in one instance removably secured to its rod member so that the rod member may be readily disconnected from the other rod member. The rod members are so connected that relative turning between them is prevented while a free longitudinal movement 25 is permitted. Means is provided for locking the rod member against relative movement and this means is so arranged that it does not mar the rod members which operate in grooves therein also serving the purpose of preventing relative movement between the rod members.

What I claim as my invention and desire to secure by Letters Patent is:

1. An extensible rod comprising two members, one of which is tubular and has the other sliding therein, a sleeve fitted in one end of said tubular member and formed with a rib on its inner side, the other member having a longitudinally extending groove 40 receiving the internal rib of the sleeve, and a combined guide and stop member arranged at the inner end of the other member of the rod and cooperating with the interior face of the tubular member to guide the inner end of said other member of the rod and also cooperating with the sleeve to limit the movement of said other member in one direction in the tubular member.

2. An extensible rod comprising a tubular member formed with a longitudinally extending internal rib, a sleeve fitting in one end of said tubular member and formed with an internal rib, a rod member movable in said sleeve and formed with a longitudinally extending external groove, and a combined guide and stop member arranged at

the inner end of said second named stop member and formed with a notch guided in the internal rib of said tubular member and cooperating with said sleeve to limit the outward movement of said second mentioned rod member.

3. An extensible rod comprising a tubular member, a collar fitted about the end of said tubular member, a sleeve fitted within 65 said end of said tubular member and formed with an internal rib, a rib member guided in said sleeve and formed with a longitudinally extending groove in which the internal rib of the sleeve operates, a combined guide 70 and stop member fitted on the inner end of said second mentioned rib member to cooperate with the sleeve to limit the outward movement of said rod member and to cooperate with the internal face of the tubular member to guide the inner end of said second mentioned rod member, a set screw 75 passing through the tubular rod and the sleeve to engage in the longitudinally extending groove of the second mentioned 80 rod member.

4. An extensible rod comprising a tubular member formed with a longitudinally extending internal rib, a sleeve fitted in the end of said tubular member and formed 85 with an internal rib, a tubular member sliding in said sleeve and formed with a longitudinally extending external groove and a longitudinally extending internal rib, a block 90 fitted within the inner end of said second mentioned tubular member and formed with a screw threaded opening, a combined guide and stop member fitted within said second mentioned tubular member and formed with a flange projecting beyond the edges of said 95 tubular member, said flange being notched to receive the internal longitudinally extending rib of the first mentioned tubular member and arranged to cooperate with the end of the internal sleeve of the first mentioned tubular member to limit the outward movement of the second mentioned tubular member, and a bolt passing through said 100 combined guide and stop member and anchored in the screw threaded opening of 105 said block.

5. An extensible rod comprising a tubular member, a sleeve at the inner end of said tubular member acting as a stop, a second rod member guided in said sleeve, 115 and a combined guide and stop member removably secured to the inner end of said second mentioned rod member, guided on the interior walls of the first mentioned rod member and cooperating with the internal 120 sleeve of said first mentioned rod member.

WILLIAM J. WOERNER.
